UNITED STATES PATENT OFFICE.

GEORGE REHFUSS, JOHN GEORGE REHFUSS, AND MARTIN O. REHFUSS, OF PHILADELPHIA, PENNSYLVANIA.

SEWING-MACHINE FOR FORMING FRINGE UPON FABRICS.

SPECIFICATION forming part of Letters Patent No. 469,452, dated February 23, 1892.

Application filed December 1, 1890. Serial No. 373 205. (No model.)

To all whom it may concern:

Be it known that we, GEORGE REHFUSS, JOHN GEORGE REHFUSS, and MARTIN O. REHFUSS, citizens of the United States, and residents of Philadelphia, Pennsylvania, have invented certain Improvements in Machines for Forming Fringe upon Fabrics, of which the following is a specification.

Our invention consists of certain improvements in the fringing-machine forming the subject of our patent, No. 438,427, dated October 14, 1890, the objects of our present improvements being to provide for the formation of a double fringe instead of the single fringe produced by said patented machine, and to improve certain details of the mechanism whereby the cutting of the fringe-loops is effected. These objects we attain in the manner hereinafter set forth, reference being had to the accompanying drawings, in which—

Figure 1 is a transverse section of a fringing-machine constructed in accordance with our present invention. Fig. 2 is a rear view of the same. Fig. 3 is a sectional plan view on the line 1 2, Fig. 1. Fig. 4 is a similar view showing some of the parts in a different position, and Fig. 5 is a detached view of part of the machine.

A A represent the supporting-frames, B the work-table or bed of the machine, a the needle, b the presser-foot, and d the feed-dog, all of which parts may be substantially similar to those shown and described in the former machine and operated in the same manner.

The present machine has, as in the former case, a hooked looping-arm D, which is secured to a rock-shaft D', having an arm D², to a slot f, in which is adapted the securing-bolt f' at one end of a rod F, the opposite end of which is connected to the sleeve of an eccentric F' upon the driving-shaft G, so that a vibrating motion can be imparted to the hooked arm D and the latter thus caused to catch the needle-thread at a point below the table and draw said thread down into a loop below the fabric, the loop being then severed by a sliding knife H, so as to form on the fabric projecting strands. The length of loop drawn by the looper-arm D may be varied by shifting the connecting-bolt f' of the rod

F in the slot f in the arm D², so as to carry it nearer to or farther from the rock-shaft D', and thus increase or diminish the throw of the looper-arm. In order that this variation in the throw of the looper-arm may not affect the throw of the knife H, the knife-slide H' has a pin g, which is adapted to a segmental slot g' in an arm I, hung to a short rock-shaft h, which is free to turn in bearings h' on the under side of the table, said rock-shaft having another arm I', which is connected to a rod I², the rear end of the latter being forked, as shown by dotted lines in Fig. 1, so as to embrace the shaft G, and said rod having a pin i, which is adapted to a cam-slot i' in a disk I³ on said shaft G. The slot g' in the arm I is concentric with the axis of the rock-shaft D' when the knife is in the retracted position. Hence the vibrating movement of the looper-arm will have no effect whatever upon the knife, the movement of the latter being caused wholly by the swinging of the arm I under the influence of the cam-disk I³ and the connections described.

The present machine is also adapted, as before stated, for the formation of a double fringe—that is to say, loops of needle-thread are drawn above the work table or bed and above the fabric in addition to the loops drawn below the same—so that fringing-strands are formed upon each side of the fabric instead of upon but one side of the same. The upper looper-arm J has a head J', which is suspended by a bolt m from the projecting end of a bracket K, secured to the table B of the machine, and vibrating motion is imparted to said looper-arm by means of a scroll-cam J² on the shaft G, this cam acting on a lever J³, which is hung to a bracket J⁴, the upper end of said lever J³ being connected to the head J' of the looper-arm J by means of a rod J⁵. The looper-arm J has a knife-slide M, the rear end of which has a pin n for engagement with the forked end of a lever N, hung to the under side of the bracket K, the other end of this lever being slotted for the reception of the upper end of a lever P, which is hung to one of the side frames of the loom, and has an anti-friction roller acted upon by a cam-disk P' on the shaft G, (see Fig. 5,) a spring P² keeping the roller in contact with the disk,

so that a vibrating motion can be imparted to said lever P at the proper time, which motion is transmitted through the medium of the lever N to the knife-slide M. When the 5 knife-slide M is retracted, the pin n is directly in line with the axis of the arm J, so that the vibration of said arm has no effect upon the knife-slide.

- In order to retain the outer end of the upper fringing-strands in position after the loops have been cut, we employ a retaining-finger S, which is carried by a rock-shaft S', mounted in bearings s on the table B, this rock-shaft having an arm S², which is connected by a rod 10 T to the upper end of the lever P, so that as the looper-arm J swings toward the left from the needle to draw the loop and the knife M moves forward on the same the finger S will be raised to permit the looper-arm J to draw the loop 15 of thread beneath the same, and after the knife has cut the loop and is retracted the finger S will descend, so as to retain the cut strands, the looper-arm moving back over the finger in order to again catch the needle-thread to draw a fresh loop. 20

Having thus described our invention, we claim and desire to secure by Letters Patent—

1. The combination of the vibrating looper-arm and the knife-slide carried thereby with 25 a knife-operating arm having a segmental slot concentric with the axis of vibration of the looper-arm when the knife is retracted and means for vibrating said knife-operating arm, substantially as specified.
2. The combination, in a machine for forming fringe upon fabrics, of the single needle, the work-table or bed, two hooked loopers, one above the bed and the other beneath the bed, and mechanism for vibrating said loopers, so as to cause them to engage with the needle-thread and form projecting unconfined loops of said thread above and below the fabric, substantially as specified. 30
3. The combination of the work-table or 40 bed, the single needle, a looper-arm vibrating

in a substantially vertical plane beneath the bed, and a looper-arm vibrating in a substantially-horizontal plane above the bed, both of said looper-arms being adapted to engage with the single needle-thread and to form projecting unconfined loops of the same, substantially as specified. 50

4. The combination, in a machine for forming fringe upon fabrics, of the needle, the work-table or bed, and two vibrating loopers, 55 one above the bed for engaging with the needle-thread on one side of the fabric and forming a projecting loop of said thread and the other beneath the bed for engaging with and forming a projecting loop of the needle-thread 60 on the other side of the fabric, both of said loopers being combined with knives for cutting the loops formed thereby, substantially as specified.

5. The combination of the work-table or 65 bed, the needle, a looper-arm vibrating in a substantially-vertical plane beneath the bed, and a looper-arm vibrating in a substantially-horizontal plane above the bed, both of said looper-arms being adapted to engage with the 70 needle-thread and form projecting loops of the same and each arm being combined with a knife for cutting the loop formed thereby, substantially as specified.

6. The combination of the upper looper 75 and means for vibrating the same, a knife-slide carried by said upper looper, a lever engaging with said knife-slide at a point coincident with the axis of rotation of the looper, and means for vibrating said knife-lever, sub- 80 stantially as specified.

In testimony whereof we have signed our names to this specification in the presence of two subscribing witnesses.

GEORGE REHFUSS.
